REPORT FOR UNDERFEED STOKERS

John C. Bohmker, Kankakee, Ill.

Application April 22, 1937, Serial No. 138,403

14 Claims. (Cl. 110—45)

This invention relates to retorts or burners for automatic coal stokers and particularly to improvements in the construction of such devices and the means for distributing air for combustion.

The main objects of this invention are to provide an improved retort construction; to provide an improved arrangement for distribution of air to the interior of the retort and to the surrounding fuel bed; to provide a retort construction in which the tuyères are less likely to become choked or clogged; to provide an improved tuyère construction; to provide an improved tuyère arrangement whereby air will be distributed equally to all parts of the fuel bed; and to provide an improved and simplified retort construction wherein burned out or damaged sections can be readily replaced.

An illustrative embodiment of this invention is shown in the accompanying drawings in which:

Fig. 1 is a perspective view of the improved coal-burning retort and its fuel supply tube.

Fig. 2 is an enlarged plan view of the same showing its formation and arrangement.

Fig. 3 is an enlarged fragmentary detail taken on line 3—3 of Fig. 2 illustrating the tuyère arrangement.

Fig. 4 is an enlarged fragmentary sectional view taken on line 4—4 of Fig. 3 showing the arrangement of tuyères for lateral air distribution to the surrounding fuel bed.

Fig. 5 is a sectional view of the improved retort as taken on line 5—5 of Fig. 2, showing the same as positioned in the combustion chamber of a furnace or boiler.

Fig. 6 is a sectional view taken on line 6—6 of Fig. 5 showing the arrangement of the lower tuyère ring.

Fig. 7 is a similar view taken on line 7—7 of Fig. 5 showing the arrangement of the upper tuyère ring and,

Fig. 8 is a fragmentary perspective detail of the tuyère rings illustrating the interlocking means for the tuyère rings and the arrangement of air channels leading to the uppermost air ports.

In the form shown in the drawings, my improved retort comprises a base section 1, a top section or shell 2 and a retort body within said shell comprising an upwardly extending body member or ring 3, a lower tuyère member or ring 4, and an upper tuyère member or ring 5; all arranged to provide an open ended retort into which coal for combustion is supplied by a worm conveyor 6 operating in a conveyor tube 7 and

entering the retort through an intake 8 leading into an upwardly curved throat portion 9 which discharges upwardly into the body ring 3 of the retort.

The throat portion 9 is formed integral with the retort base 1 and the floor 10 of the throat is curved upwardly in a mathematical curve which is known as the Schiele antifriction curve. This construction of the retort throat equalizes the friction over the curved floor of the same so that less power is required to force the fuel from the conveyor 6 into the retort.

As shown, the tuyère rings 4 and 5 are arranged to fit and nest one above the other, on top of the body ring 3. The retort shell 2 is spaced away from the retort body and is formed with an inwardly turned flange-like portion 11 at its upper end and the inner margin of the portion 11 is turned downwardly so as to nestingly engage the upper tuyère ring 5. Thus, means is provided to connect the vertical side wall of the shell 2 with the upper edge of the uppermost tuyère ring 5 and close off the space between the shell 2 and the retort body.

The body ring 3 and the tuyère rings 4 and 5 are formed so that when assembled the retort will have a smooth upwardly and outwardly sloping side wall which extends flush with the inner margin of the inturned portion 11 of the shell 2, thus forming a retort pot which extends upwardly from the throat portion 9 with a gradually increasing horizontal area.

The body ring 3, which is shown in the form of an inverted truncated cone, is arranged to fit onto the throat portion 9 as shown in Fig. 5 and a lug or key 12 is provided on the bottom margin of the body ring 3 for interlocking engagement with a notch formed in the upper edge of the throat 9, so that when the body ring 3 is set thereon, its proper angular position will be fixed. The purpose of so positioning the ring 3 will subsequently be shown.

The upper margin of the body ring 3 is provided with an annular groove 13 on its inner periphery to receive a depending annular flange-like portion 14 on the inner lower margin of the tuyère ring 4 which is arranged to be nestingly set upon the body ring 3.

Also the inner upper margin of the tuyère ring 4 is provided with a similar groove 15 into which an annular depending flange 16 on the inner bottom margin of the tuyère ring 5 fits. Likewise the upper margin of the tuyère ring 5 is formed to provide a seat into which a downwardly extend-

ing lip 17 of the inwardly-turned portion 11 of the shell 2 is arranged to set.

Thus, when the several rings comprising the pot or body portion of the retort are properly assembled and the shell 2 is set thereupon and bolted down to the base portion 1, the entire retort becomes a unit in which the several parts are securely locked together.

As shown, the tuyère rings 4 and 5 are arranged to provide angularly spaced horizontal slot-like ports or tuyères 18 and 19 respectively, which ports provide communication between the interior of the retort and space 20 between the shell 2 and the retort rings. The space 20 communicates with an air space 21 surrounding the throat portion 9 of the retort base and the space 21 leads to openings 22 and 23 disposed on either side of the throat inlet portion 8. The opening 22 is arranged for connection to an air supply duct 24 and the opening 23 is arranged as a cleanout passage for the removal of fly ash. Thus, air delivered into the opening 22 circulates through the space 21 surrounding the throat portion 9 and thence upwardly into the space 20, surrounding the retort body or pot, from which it passes through the ports 18 and 19 into the interior of the retort.

In order to provide for the lateral distribution of air to the fuel bed above and surrounding the top of the retort, a plurality of spaced ports 25 are provided in the upper flange-like portion 11 of the shell 2. As shown, the ports 25 communicate with the air space 20 within the shell 2 vertically, through the inwardly-turned portion 11, and each air port 25 is provided with a rounded hood 26 which is integral on the flange-like portion 11 and which is shaped to direct air from the ports 25 radially outward from the upper end of the retort and into the surrounding bed of fuel. The several hoods project upwardly above the inturned portion 11 of the shell 2 and are in the nature of an angularly spaced series of bosses. Also, as shown, each of the hoods is tapered inwardly toward the axis of the retort.

As shown in Figures 6 and 7, the air ports or tuyères 18 and 19 are spaced angularly relative to the axis of the tuyère rings and are formed by providing horizontal peripherally extending slots in the upper surface of the tuyère rings, as by cutting away or omitting portions from the tuyère ring surface and, as shown, each port or slot extends into the ledge or shoulder formed by the inner peripheral groove at the upper margin of the tuyère ring; thus each port is stepped downwardly as shown in Figure 5, so as to clear the annular flange at the bottom of the member next above.

In order to provide for equal distribution of air for combustion, the air ports or tuyères 19 of the tuyère ring 5, which is nearest to the burning fuel bed, are of varying size in the peripheral direction, though their centers are equally spaced apart angularly, and the disposition of the air ports 19 is particularly arranged so that the largest ports are at the location of the lowest pressure in the air space 20 surrounding the tuyère rings.

Since the incoming air for combustion enters the base portion of the retort at one side thereof, in the direction shown by the arrow 27 in Figs. 2 and 7, parallel to the fore and aft center line, indicated by the line A—A in Fig. 7, it will be apparent that the air pressure in the space 20 will vary according to the distance from the point

of entry. Hence, if the retort is considered as being divided into quadrants by the transverse center line B—B the first quadrant I will have the highest pressure and the third quadrant III will have the lowest pressure. Quadrants II and IV have a substantially equal pressure, for the reason that, in the arrangement shown, the incoming air divides in the quadrant I and passes in both clockwise and counterclockwise directions toward quadrant III.

Thus, the air ports 19 in quadrant I are made to be the smallest and the air ports in quadrant III are made to be the largest. The air ports in quadrants II and IV are substantially equal and are of a size intermediate the sizes for quadrants I and III. In this manner the volume of air passing through the several air ports 19 will be substantially equal for each air port around the entire periphery of the tuyère ring.

While such an arrangement of the air ports 18 in the tuyère ring 4 is not shown herein, it will be understood that the air ports 18 may be also of graduated sizes according to the quadrant in which they are located.

In order that the tuyère rings 4 and 5 will be certain of proper angular location relative to the several quadrants, the tuyère ring 4 is keyed to the body ring 3 as at 28, Fig. 8, and the tuyère ring 5 is keyed to the tuyère ring 4 as at 29, the body ring 3 being keyed to the mouth of the throat portion 9 by the lug 12 as shown in Fig. 5.

As shown in Figs. 3, 5, and 8, the tuyère ring 5 is notched or grooved vertically on its outer peripheral surface, opposite each of the air ports 25 at the top of the shell 2, as indicated at 30, to provide a channel or guide to direct air from the space 20 to the air ports 25. Also in order to provide equal distribution of air to and through the air ports 25, the upper tuyère ring 5 is formed so that its upper outer peripheral edge is eccentric relative to the axis of the ring 5, as shown in Fig. 7. Thus the outermost periphery of the tuyère ring 5 is nearest the wall of the shell 2 in quadrant I and farthest from the wall of the shell 2 in the quadrant III, in this manner serving to block off or throttle the air passing to the air ports 25 in the quadrant I, while the air ports 25 in the quadrant III are permitted a larger space through which air can pass from the air space 20.

It will now be seen that the herein described arrangement, a coal-burning retort of simplified construction and lower cost of manufacture is provided; and likewise by means of the construction, an equal distribution of air to all parts of the fuel bed is accomplished automatically, regardless of the amount of air that is delivered to the wind box or air space 21, in the base portion 1, through the air supply duct 24 which is preferably connected to a motor-driven blower, not shown.

In use the improved retort is set into the ash pit of a furnace or boiler, so as to be centrally positioned therein. The retort is set up by first placing the base portion 1 and then setting thereupon the retort body ring 3 and the tuyère rings 4 and 5 after which the shell 2 is set in position and bolted down, as indicated in Fig. 1. The furnace or boiler ash pit is then filled in with a suitable refractory material up to a level about one inch or an inch and a half below the hooded openings of the air ports 25; from which point the refractory material is tapered upwardly toward the side walls of the furnace or boiler combustion chamber.

In operation coal is forced into the retort by means of a screw or worm conveyor 6 and upwardly therethrough into the furnace combustion chamber, where it tends to flow outwardly 5 toward the side walls of the same.

As the coal is supplied upwardly through the retort from the throat portion 8, air for combustion is at the same time supplied to the wind box 21 and combustion takes place at the top 10 portion of the retort, spreading outwardly through the bed of fuel above the retort toward the sides of the furnace combustion chamber.

Because of the equal distribution of air, accomplished by the herein described tuyère arrangement, the fuel is burned uniformly about 15 the entire periphery of the retort and the portion of the fuel bed lying immediately within the top portion of the retort is uniformly heated.

The hooded lateral ports 25 at the top of the 20 retort serve to distribute air to the surrounding bed of fuel and at the same time boss-like hoods 26 serve to break up the solid mass or body of the coal as it reaches the top edge of the retort and is forced over the same into the space 25 beyond or surrounding the retort. Thus, free access of air into the mass of fuel is assured to promote uniform and complete combustion. Without such breaking up of the fuel mass, as it passes over the top edge of the retort, the 30 fuel would very shortly form a solid ring of coke around the outer shell of the retort and thereby prevent sufficient air to pass into the fuel mass for complete combustion of the same.

It will also be seen that the movement of the 35 fuel upward through the retort in no way obstructs the hooded air ports 25 and while the air ports or tuyères 18 and 19 are exposed to clogging by reason of sliding contact with the fuel, the fact that they are extended in a horizontal 40 direction, instead of a vertical direction as is usually the case, tends to minimize such obstruction.

The main advantages of my improved retort lie in the simplicity of its construction and its 45 readily replaceable parts as well as in the arrangement providing for a more equitable distribution of combustion air to the fuel bed.

Other advantages lie in the substantially non-clogging arrangement of the air ports or tuyères opening into the interior of the retort; and in 50 the hooded tuyère openings or air ports 25 which deliver air laterally outwardly from the upper portion of the retort, the hoods serving not only to prevent clogging of these lateral air ports but also serving to break up the mass of fuel as it 55 flows over the top edge of the retort.

It will be understood, that, while the retort herein shown and described, is of a circular construction, the invention herein set forth is equally applicable to other retort shapes such as an 60 elliptical shape or every adaptation of the polygon.

Although but one specific embodiment of this invention is herein shown and described, it will be understood that details of the construction shown 65 may be altered or omitted without departing from the spirit of this invention as defined by the following claims:

I claim:

1. A retort of the class described comprising 70 an upwardly extending open-ended body, a shell spaced from and surrounding said body, flange-like means connecting the upper ends of said shell and body and closing off the space therebetween, and a hollow support for said shell opening upwardly into said space and having a lat-

eral air inlet, said body having a plurality of perimetricaly spaced ports therethrough communicating with the said space, said ports being proportioned to provide a progressively increasing port area in successive predetermined 5 perimetric segments of said body as said segments become perimetricaly remote from the location of said air inlet and a decreased port area as said segments again approach said air inlet location in the same perimetric direction. 10

2. A retort of the class described comprising an upwardly extending open-ended body, a shell spaced laterally from and surrounding said body, flange-like means connecting the upper ends of said shell and body and closing off the space 15 therebetween, and a hollow support for said shell opening upwardly into said space and having a lateral air inlet, said body having a plurality of vertically narrow horizontally extending perimetricaly spaced ports in its side wall 20 communicating with the said space, said ports increasing in horizontal length as they progress in both perimetric directions from the side of said body adjacent said air inlet to the opposite side thereof. 25

3. A retort comprising an upwardly extending body member, a pair of horizontally disposed tuyère members fitted one upon the other and upon the upper end of said body member, each of said tuyère members having a plurality of 30 ports perimetricaly spaced in its side wall, said ports being proportioned to provide a greater port area in one side of said retort than in the opposite side thereof, a shell member spaced laterally from and surrounding said body and 35 tuyère members, said shell member having an inwardly turned upper margin fittingly engaging the margin of the uppermost tuyère member, and a hollow base supporting said shell member, said base having upward communication with the 40 space between said shell and body members and a lateral air inlet located adjacent the side of said retort having the smallest port openings.

4. A retort comprising an upwardly extending body member, a pair of horizontally disposed 45 tuyère members fitted one upon the other and upon the upper end of said body member, each of said tuyère members having a plurality of ports perimetricaly spaced in its side wall, said ports being proportioned to provide a progressively increasing port area in successive predetermined perimetric segments of said retort which segments progress in both perimetric directions from one side of said retort to the opposite side thereof, a shell member spaced from and surrounding said 50 body and tuyère members, said shell member having an inwardly turned upper margin fittingly engaging the margin of the uppermost tuyère member, and a hollow base supporting said shell member, said base having upward communication with the 55 space between said shell and body members and a lateral air inlet located adjacent the side of said retort having the smallest port openings.

5. A retort of the class described comprising an upwardly extending open-ended body, a shell 60 spaced from and surrounding said body, flange-like means connecting the upper margins of said shell and said body, and a plurality of hollow perimetricaly spaced bosses projecting upwardly from the upper surface of said flange-like means, 65 said hollow bosses each having communication with the space between said shell and body and having a discharge port opening laterally outward relative to said shell. 70

6. A retort of the class described comprising an 75

- upwardly extending open-ended body, a shell spaced from and surrounding said body, flange-like means connecting the upper margins of said shell and said body, and a plurality of hollow inwardly tapered perimetricaly spaced bosses projecting upwardly from said flange-like means, said bosses each having a port opening laterally outward relative to said shell, and said flange-like means having spaced ports providing communication between said hollow bosses and the space between said shell and body.
7. A retort of the class described comprising an upwardly extending open-ended body, a shell spaced laterally from and surrounding said body, means connecting the top of said shell and the upper margin of said body, said last-named means having a plurality of perimetricaly spaced ports communicating with the space between said shell and said body, a hood covering each of said ports and opening laterally outward relative to said shell, said body and shell being arranged to provide a progressively increasing width of the space between their respective side walls and in the vicinity of said ports in both perimetric directions from one side of said retort to the opposite side thereof.
8. A retort comprising an annular open-ended upwardly extending body member, a pair of annular tuyère rings fitted one upon the other and upon the upper end of said body member, each of said tuyère rings having a plurality of angularly spaced tuyères opening through its side wall, said tuyères being arranged to provide a progressively increasing tuyère opening area in successive predetermined angular segments of said retort in both angular directions from one side of said retort to the opposite side thereof, an annular shell member spaced from and surrounding said body member and tuyère rings, means connecting the margins of said shell and the uppermost tuyère ring to close off the space therebetween, and a plurality of angularly spaced hollow bosses projecting upwardly from said last-named means, said bosses having communication with the space between said shell and tuyère rings and a port opening radially outward relative to said retort.
9. A retort comprising an annular open-ended upwardly extending body member, a pair of annular tuyère rings fitted one upon the other and upon the upper end of said body member, each of said tuyère rings having a plurality of angularly spaced tuyères opening through its side wall, said tuyères being arranged to provide a progressively increasing tuyère opening area in successive predetermined angular segments of said retort in both angular directions from one side of said retort to the opposite side thereof, an annular shell member spaced from and surrounding said body member and tuyère rings, means connecting the
- margins of said shell and the uppermost tuyère ring to close off the space therebetween, said last-named means having a plurality of angularly spaced openings therethrough communicating with the said closed off space each covered by a vertically projecting hood-like boss, said bosses each having a port opening radially outward from said retort, and the uppermost tuyère ring having its outer margin eccentric relative to the inner wall of said shell to throttle certain of said last-named openings.
10. In a device of the class described, a tuyère member comprising an annular ring having a plurality of angularly spaced horizontally extending slot-like tuyère openings in its side wall and an outer periphery eccentric relative to its inner periphery, said tuyère openings being of varying length as they progress angularly about said ring from the place of greatest eccentricity of said peripheries.
11. In a device of the class described, a ring-like tuyère member having a plurality of tuyère openings spaced along its side wall, said tuyère member being formed with the center of the area defined by its outer perimeter offset laterally relative to the center of the area defined by the inner periphery.
12. In a device of the class described, a tuyère member comprising an annular ring having a plurality of angularly spaced tuyère openings in its sidewall, said tuyère member being formed with its outer periphery eccentric relative to its inner periphery.
13. A retort of the class described, comprising an inwardly extending open-ended body, a shell spaced laterally from and surrounding said body, means connecting the top of said shell and the upper margin of said body, said last-named means having a plurality of laterally opening perimetricaly spaced ports communicating with the space between said shell and said body, and said body and shell being arranged to provide a progressively increasing width of the space between their respective sidewalls and in the vicinity of said ports in both perimetric directions from one side of said retort to the opposite side thereof.
14. A retort of the class described, comprising an inwardly extending open-ended body, a shell spaced laterally from and concentrically surrounding said body, means connecting the top of said shell and the upper margin of said body, said last-named means having a plurality of perimetricaly spaced ports communicating with the space between said shell and said body, and said body having its outer perimetric contour formed to provide a progressively increasing width of said space in the vicinity of said ports in both perimetric directions from one side of said retort to the opposite side thereof.

JOHN C. BOHMKER. 60
